TRACK TURNOUT OR THE LIKE

Eugene W. Caruthers, Secane, Pa., assignor to
The Pennsylvania Railroad Company, Philadelphia, Pa., a corporation of Pennsylvania

Application February 1, 1934, Serial No. 709,343

8 Claims. (Cl. 246—468)

This invention relates to railway track turnouts or the like, and is particularly directed to turnouts, crossings, crossovers, slip switches, or other so-called "special track structures", particularly those in which frogs are employed.

Heretofore it has become common practice among railroads to cant rails inwardly toward the center of the track. Such canting of the rails is generally accomplished by the use of inclined tie plates. It is believed that the canting of rails on an inclination approximating the coning of the wheels insures central loading of the rail head, especially with new rails, and it is also believed that inclined tie plates effect a better distribution of the load upon the ties. No particular difficulty is involved in canting the rails throughout ordinary sections of track, but at regions where special track structures are employed, such as turnouts, crossings, crossovers, slip switches, or the like, difficulty has been experienced in maintaining alignment between the canted rails and the frogs, the base and tread surfaces of the latter being desirably disposed in planes parallel to the top plane of the ties. According to customary practice the rails are not canted at such regions, and they are joined to the extremities of the frog irrespective of fit or alignment. When such a joint is tightened there results either an imperfect joint or else the rails are improperly supported upon the underlying tie plates.

The object of this invention, stated generally, is to overcome the aforementioned difficulties experienced in joining canted rails to frog arms or like structure, and to this end I provide a special form of frog which relieves the unsatisfactory condition at the joints.

A further object of the invention is to provide a frog or like track structure of the above character which is of simple and inexpensive manufacture and which departs to a minimum from existing standard railway frogs.

Another more specific object of the invention is to provide, in combination with such a frog, switch rails of special form which effect a transition from canted rails to vertical rails between the frog and switch points, whereby the entire structure of the turnout or the like is relieved of difficulties presented by the canting of the rails.

Another specific object of the invention is to provide a form of rolled rail, whether it be a part of a frog, or switch rail, or other structure, which is characterized by a uniform cross section and which is twisted throughout a region of its length to render a transition from a canted section to a

vertical section, the twist being so effected as to preserve the gage line at the rail head as a continuous straight line.

Other objects and advantages characterizing my invention will become more fully apparent from the description hereinafter set forth of certain embodiments or examples of the practice of the invention, the description having reference to the accompanying drawings. Of the drawings:

Fig. I represents a plan view of a track turnout embodying my invention. 10

Fig. II represents an enlarged plan view of the switch rails in the area designated at II in Fig. I.

Fig. III represents a plan view of the frog shown in the area designated at III in Fig. I, which incidentally is of the rail bound manganese type. 15

Fig. IV represents a spring rail frog embodying features of my invention.

Fig. V represents a cross section of a rail twisted about its gage line in accordance with the practice of my invention. 20

Fig. VI represents a cross section of a switch and stock rail, taken as indicated by the lines VI—VI of Fig. II. 25

Fig. VII represents a cross section of the rail arms of a frog taken as indicated by the lines VII—VII of Fig. III.

Fig. VIII represents a cross section of the switch and stock rails near the switch point, taken as indicated by the lines VIII—VIII of Fig. II; and, 30

Fig. IX represents a similar cross section, taken as indicated by the lines IX—IX of Fig. II.

With reference particularly to Fig. I of the drawings, there is shown a plan view of a turnout embodying my invention.

While a turnout has been selected for illustration, it will be readily understood from the description which follows that the invention is equally applicable to many other structures wherein one track intersects another.

In the drawings the frog is designated at 1, the connecting rails leading to its heel are designated at 2, 3 and the rails leading to its wings at 4, 5. The switch rails are designated at 6, 7, and their adjacent stock rails at 8, 9. 40

The rails abutting against the ends of the switch rails are designated at 10, 11. For convenience, all of the rails of the turnout with the exception of the switch rails 6, 7 are referred to herein as "rigid rails". 45

The rigid rails are in each instance canted toward the centers of the tracks defined by them, this being accomplished according to the customary practice by the use of inclined tie plates. Though in actual practice the rails would likely 55

be canted on an inclination of 1 in 40 or thereabouts, to illustrate the nature of the track elements clearly the inclination has been somewhat exaggerated in the drawings.

5 One form of frog embodying features of my invention is illustrated in Fig. III, and is there shown to be of the rigid type. In this example the central region of the frog designated at *a* is in all respects similar to frogs now in general use. Throughout the region *a* the tread surfaces 10 16 are flat or substantially so, as shown in Fig. VII, and the base surfaces 17 are likewise flat, while the web elements 18 are vertically disposed. In referring to "flat surfaces" herein, I use the 15 word "flat" in a relative sense and mean to indicate plane surfaces which are substantially parallel with the top plane of the ties in contrast to surfaces which are definitely inclined with respect to the top plane of the ties.

20 The point of the frog *l* is designated at 20, the heel rails at 21, 22, and the wing rails at 23, 24. The rail elements of the frog, which may be of a solid or built-up type, present diverging arms of uniform cross section at each side of the frog point. In the regions of the frog designated at *b*, 25 the heel rails 21, 22 and the wing rails 23, 24 are twisted to effect a transition from a vertical section to a canted section.

20 In order to preserve the gage lines of the frog (theoretical lines extending through the point *x* at the gage sides of the heads just below the running surface) as continuous straight lines, the twist at the regions *b* is accomplished, as illustrated in Fig. V, by displacing the head, web and base about the axis *x* or an axis substantially coincident with the gage line at the rail head. This displacement of the rails does not affect the gage lines, and produces rail sections at opposite sides of the region of twist having plane bases inclined at an acute angle *z* with each other. Moreover, by twisting the rails about the axis *x*, the vertical distance of the lowest points of the flat and inclined bases above the ties is substantially the same as indicated in Fig. V. 45 Accordingly, standard tie plates having flat surfaces may be used to support the rails at one side of the region of twist and standard inclined tie plates may be used at the other side.

50 At the regions of the extremities of the frog designated at *c* in Fig. III, the diverging rail arms are of uniform section with their tread surfaces 16a and base surfaces 17a inclined downward toward their gage sides and with their web elements 18a inclined from the perpendicular, as 55 clearly shown in Fig. VII.

In Fig. IV I have shown the application of my invention to a standard frog of the spring rail type. Throughout the central region *a*, embracing the frog point 27, the tread and base surfaces of the point rails 28, 29 of the rigid and movable wing rails 30, 31 are flat and their web elements are vertically disposed with respect to the ties. At the transition regions *b* the point rails 28, 29 and wing rails 30, 31 are twisted in the manner already described with reference to the solid railbound frog of Fig. III. At the outermost regions *c* the point rails 28, 29 and wing rails 30, 31 are canted toward their gage sides. It will be noted that the spring or movable wing rail 31 has a flat base surface throughout the throat of the frog and that it therefore bears uniformly upon the base plate 32.

With both types of frogs represented in the drawings, the extremities are canted in such manner as to produce perfect alignment at the rail

5 joints between the point and wing rails of the frog and the abutting rails 2, 3, 4, 5, of the turnout.

It is to be noted that all of the rigid rails of the turnout including those specifically designated at 2, 3, 4, 5, 8, 9, 10 and 11 are canted toward the track center lines. In order to insure the proper operation of the movable switch rails 6, 7, these rails are specially designed as shown in Figs. II and VI.

10 The switch rails 6, 7 are canted at their heel ends through the regions designated at *d*. Throughout the regions *e* the switch rails 6, 7 are twisted, without displacement of the gage lines; and throughout the regions *f* which include the 15 switch points, the switch rails have flat bases and tread surfaces and vertically disposed web elements. At the switch points the relation of the switch rails to the stock rails is as represented in Figs. VIII and IX. In Fig. VIII the switch 20 rail 6 is closed with respect to the stock rail 8. The stock rail 8 is canted and rests upon the inclined seat 33 of the gage plate 34. The stock rail is held rigidly in place by an adjustable rail brace 37 of conventional type. On the other 25 hand the switch rail 6 is vertically disposed with its flat base 35 resting upon the horizontal top surface 36 of the gage plate. As shown in Fig. IX, when the switch rail 7 is opened with respect to its stock rail 9, by reason of the fact that the 30 flat base of the switch rail and the top surface 36 of the gage plate 34 are disposed in horizontal planes, there is uniform bearing between these elements. Hence opening and closing of the switch can be effected smoothly and without 35 causing the bases of the switch rails to wear unevenly.

From the above description it will be apparent that the incorporation in a railway turnout or the like of frogs and switch rails twisted in the 40 manner described solves the problem of canting rails throughout such special track structures, without displacing the gage lines, or disturbing the alignment of abutting rails at the joints, or 45 affecting the uniform bearing of movable elements of the structure on the underlying plates.

While I have referred to certain specific embodiments of my invention, which have been described in some detail, it will, of course, be apparent that many changes may be made in the 50 particular apparatus described without departing from the spirit of my invention as defined in the annexed claims.

Having thus described my invention, I claim:

1. A railway track turnout or the like comprising rigid rails canted toward the centers of the tracks, a frog having its extremities canted and aligned with the ends of the abutting rigid rails and having a central portion with a flat base, and switch rails having their heels canted and aligned with the ends of the abutting rigid rails, said switch rails having flat bases at the 55 switch points.

2. A railway track turnout or the like comprising rigid rails canted toward the centers of the tracks, a frog having rail arms at the heel and toe canted and aligned with the ends of the abutting rigid rails and having a flat base throughout the region of the frog point, and switch rails having their heels canted and aligned with the ends of the abutting rigid rails, said switch rails having flat bases at the switch points.

3. A railway track turnout or the like comprising rigid rails canted toward the centers of the tracks, a frog having a flat base throughout 75

- the region of the frog point and having arms at the heel and toe twisted without displacement of the gage lines to afford canted extremities aligned with the ends of the abutting rigid rails, and switch rails having flat bases at the switch points, said switch rails being twisted without displacement of their gage lines to afford canted heels aligned with the ends of the abutting rigid rails.
- 5 4. A railway frog comprising a central portion having a flat base and diverging arms at the heel and toe twisted beyond the region of the frog point to afford canted extremities.
- 10 5. A railway frog comprising a central portion having a flat base and diverging arms at the heel and toe twisted without displacement of the gage lines to afford canted extremities.
- 15 6. A railway frog comprising heel and wing rails, the bases of said rails being flat throughout the region of the frog point, and said rails being twisted without displacement of their gage lines in regions at each side of the frog point

whereby their ends are canted toward the gage sides of the rails.

7. A railway frog comprising heel and wing rails, the bases of said rails being flat throughout the region of the frog point, and said rails presenting diverging arms of uniform cross section at each side of the frog point, said arms being twisted without displacement of their gage lines to afford canted extremities.

5 8. A special railway track structure having a region of uniform rolled rail cross section, one end portion of said region having a plane base inclined at an acute angle with respect to the base of the other end portion, and characterized by an intermediate portion twisted bodily about the gage line of the rail head, the uniformity of the cross section and the continuity of the gage line being preserved throughout the intermediate and the end portions.

EUGENE W. CARUTHERS.
